COMMODITY PACKAGE

John J. Cavanagh, Farmingdale, N. Y.

Application December 18, 1934, Serial No. 758,022

3 Claims. (Cl. 46—11)

This invention has to do with commodity packages and comprehends a novel form of container for the packaging of children's candies or other commodities or combination of commodities.

Broadly stated, the invention consists of a box for packaging a juvenile commodity or combination of such commodities, particularly children's candies and one or more marbles in which the box is so constructed and arranged as to display the contents so as to make for a greater appeal to prospective purchasers and thereby render the package and its contents more attractive and salable.

As a further feature, the invention provides a package of the indicated character which, in addition to serving as a container for the commodities, is so constructed as to also function in conjunction therewith as a toy or amusement device for a child.

The invention more particularly resides in a package of the type specified, which bears thereon a character, either real or fanciful, with an opening representing a portion of the character and with a marble, spheroidal candy or other commodity arranged within the body of the package, projecting partially through the opening and retained in juxtaposition thereto by the edge of the opening so that the projecting portion may be utilized to turn the commodity with reference to the openings for exposing to view various portions of the surface thereof.

More specifically, the invention contemplates a package of the character set forth which bears thereon the face of a person, either real or fanciful, or that of an animal or creature, with openings representing the eye openings and with marbles, spheroidal candies, or other commodities arranged in juxtaposition to said openings to simulate the eyes, and which are adapted to be turned by the portion thereof projecting through the opening, so as to assume relatively different positions, lending thereto varying and amusing effects.

As a still further object, the invention provides a packaged commodity or combination of commodities, including a box-like body having opposed walls provided with aligned openings and a spheroidal commodity within the body projecting partially through the aligned openings in the opposed walls so as to retain the commodity in juxtaposition thereto by engagement with the edges of the openings and whereby one of the projecting portions thereof may be uti-

lized to turn the commodity with reference to the openings for obtaining amusing effects.

The invention, furthermore, aims to provide a commodity package of the character specified, which is comparatively simple, inexpensive to produce and which is of a highly amusing and attractive nature.

With the above enumerated and other objects in view, reference is made to the following specification and accompanying drawing, in which there is set forth, by way of example, several preferred embodiments of the invention, while the appended claims cover variations and modifications thereof which fall within the scope of the invention.

In the drawing:

Fig. 1 is a view in elevation of a commodity package embodying the invention.

Fig. 2 is a vertical sectional view taken approximately on line 2—2 of Fig. 1.

Fig. 3 is a horizontal sectional view taken approximately on line 3—3 of Fig. 1.

Fig. 4 is a view in elevation of a commodity package illustrating a modified form of the invention.

Fig. 5 is a horizontal sectional view taken approximately on the line 5—5 of Fig. 4.

Referring by characters of reference to the form of the invention illustrated in Figs. 1 to 3 inclusive of the drawing, 10 designates a container which may be of any preferred form or character for packaging one or more juvenile commodities or combinations thereof, such as candies and spherical toys. The container 10 which as shown is of oblong formation and of relatively narrow depth in proportion to its height and width, is particularly designed for the packaging of candy sticks 11 and one or more marbles 12, two marbles being shown in the embodiment illustrated in Figs. 1 to 3 inclusive.

In addition to serving as a container for the packaging of candies and marbles, the container 10 is so constructed as to function, in conjunction with one or more of the marbles, as a toy or amusement device for a child. For this purpose, the container is provided on the outer face of one of the walls thereof, or, if desired, on the outer faces of opposite walls, with a character, representation or image, either real or fanciful, such as a picture or face 13 and with one or more aligned openings 14 in opposite walls thereof representing a portion of the picture of the face 13, such as an eyeball. The marble 12, or other spherical commodity, is packaged within the container so as to project partially through the

aligned openings 14 in the opposite walls thereof and which is held in juxtaposition to the openings by engagement with the edges thereof, whereby the portions of the marble or commodity 5 projecting through the openings may be actuated or manipulated by a child to cause the marble to roll or turn with reference to the opening for obtaining amusing effects. The marbles or other commodities used are preferably of the "blotch" 10 or "streak" type, that is, they are formed with variegated surfaces or differently colored or shaded peripheral portions to obtain the effects desired by turning the same with reference to the openings in the package.

15 Obviously, in the form of the invention disclosed in Figs. 1 to 3, the portions of the spheroidal commodities projecting from one side of the package may be engaged with a surface and rolled thereover so as to simultaneously cause the turning 20 of the commodities to produce the moving effects.

In the form of the invention illustrated in Figs. 4 and 5 of the drawing, the package or container 15 is provided with a circular opening 25 16 in one wall 17 thereof and in this instance the spheroidal commodity 18 has a portion thereof projecting through said opening 16, while the opposite wall 19 of the package or container bears against the portion of the commodity 18 diametrically opposite the opening. Obviously, in 30 this instance, the commodity 18 is turned with reference to the opening by utilizing the portion which protrudes through the opening.

What is claimed is:

35 1. A package for juvenile commodities, comprising a box-like body having opposite walls formed with aligned openings therein and a spheroidal commodity within the body having a variegated surface with portions thereof projecting partially through the aligned openings

and retained in juxtaposition thereto by the edges of the openings, whereby the portions projecting through one of the openings may be utilized to turn the commodity with reference to the openings, for exposing to view various portions of the surface thereof. 5

2. A package for juvenile commodities, comprising a box-like body including opposed walls, the outer face of one of said walls bearing the representation of a character or image and said walls having aligned openings therein, the opening in one of said walls representing a portion of said character or image and a spheroidal commodity arranged within the body, having a variegated surface and cooperating with one of said 10 openings to form a part of the image, said commodity having diametrically opposite portions projecting partially through the openings and retained in juxtaposition thereto by the edges of the 15 openings, whereby the projecting portions may be utilized to turn the commodity with reference to the openings, for exposing to view various portions of the surface thereof to give amusing effects to the image. 20

3. A package for juvenile commodities, comprising a box-like body including opposed walls, the outer face of one of said walls bearing a representation of an image, and in one of the walls being formed with an opening, the opening in one 25 of the walls representing a portion of the image and a spheroidal commodity within the body combining with said opening to form a part of said image, and having a portion of the periphery thereof projecting partially through said opening and retained in juxtaposition thereto by the 30 edges of the opening whereby said projecting portion may be utilized to turn the commodity with reference to the opening in the package. 35

JOHN J. CAVANAGH. 40

CERTIFICATE OF CORRECTION.

Patent No. 2,085,414.

June 29, 1937.

JOHN J. CAVANAGH.

It is hereby certified that error appears in the printed specification of the above numbered patent requiring correction as follows: Page 2, second column, line 28, and lines 29 and 30, claim 3, strike out the words "in one of the walls"; and that the said Letters Patent should be read with these corrections therein that the same may conform to the record of the case in the Patent Office.

Signed and sealed this 21st day of September, A. D. 1937.
